BOTTLE CAP OR CLOSURE

Beat Kuhne, Lewistown, Mont.

Application January 8, 1934, Serial No. 705,790

6 Claims. (Cl. 215—46)

This invention relates to bottle caps or closures and more specifically to improvements in bottle caps such as disclosed in Patent No. 1,612,927 granted to me on January 4, 1927. In said patent is disclosed a bottle cap embodying means whereby a portion of the cap may be swung so as to sever a portion of the sealing disc and provide an opening in the cap thru which the contents of the bottle may be poured.

10 The primary object of the present invention is to provide a bottle cap or closure of this character embodying an arrangement to assure severing of a substantial portion of the sealing disc so that the contents of the bottle may be poured freely.

15 A further object of the present invention is to provide an improved bottle sealing cap of this character permitting removal of the contents of the bottle without the necessity of employing

20 some form of instrument to wholly remove the cap from the bottle, and which cap will also allow for subsequent closing of the bottle after partially removing the contents thereof.

25 Other objects and advantages of the invention will be apparent during the course of the following detailed description, taken in connection with the accompanying drawings, forming a part of this specification and in which drawings:—

30 Figure 1 is a top plan view of the cap constructed in accordance with the present invention.

Figure 2 is a view looking at the inner side of the cap.

35 Figure 3 is a sectional view thru the cap on line 3—3 of Figure 1 and showing the cap in position closing the bottle.

Figure 4 is a sectional view on the line 4—4 of Figure 1.

40 Figure 5 is a sectional view showing the cap opened to permit the contents of the bottle to be poured out thru an opening formed in the cap.

Figure 6 is a view looking at the inside of the metal cap with the yieldable sealing disc removed.

Figure 7 is a perspective view of the opener member for the cap.

Figure 8 is an inside plan view showing the modified form of cap.

Figure 9 is a plan view looking at the inner side of the metallic cap shown in Figure 8.

50 Figures 10 and 11 are sectional views on the respective lines in Figure 8.

Figure 12 is a sectional view showing the cap of Figure 8 opened.

Figure 13 is a perspective view of the major or

outer portion of the cap opener shown in Figures 8 to 12.

Figure 14 is a perspective view of the inner member or plate section for the opener shown in Figure 13.

5 Referring first to the form of bottle cap or closure shown in Figures 1 to 7 inclusive, the same comprises a metallic cap 10 having the form of the well known crown cap and embodying a disc-shaped top portion 11 provided about its edge 10 with the usual scalloped flange 12 adapted to be crimped about the end of the neck of the bottle A to form a closure therefor. Provided on the cap 10 is an opener member 14 capable of being swung with respect to the cap for severing a substantial portion of the sealing disc 15 whereby an opening is formed thru the bottle closure so that the contents of the bottle may be poured out.

Formed in the top portion 11 of the cap 10 is 20 an elongated, preferably rectangular-shaped opening 16 provided along each of its longer side edges with an inwardly extending blade or cutter 17. These parallel blades 17 as will be observed in Figure 4, are formed as a part of the top portion 11 and have a depth less than the thickness of the sealing disc 15 so that there is an uncut portion of the disc beneath the edges of the blades. Formed integral with the top portion 11 and bent inwardly therefrom at one end of the 25 opening 16 is a tongue or arm 18 adapted to extend with a sealed fit thru the sealing disc 15. As shown more clearly in Figure 6, this tongue is of a width less than the width of the opening 16 to provide material for formation of the blades 30 35 17 throughout the length of the opening 16.

Referring now to the opener member 14, the same is preferably formed of suitably thin metal and of one piece construction providing an attaching portion 20 which is secured at one end as 40 by soldering, welding or the like to the outer side of the top portion 11 at that end of the opening 16 from which the tongue 18 is inwardly bent. Struck inwardly from this attaching portion 20 is an inner plate portion 21 connected at one end 45 to the free end of the portion 20 by an arm 22 which extends with a sealed fit thru the sealing disc 15 adjacent one end of the opening 16. This inner plate 21 which is adapted to overlie the inner face of the sealing disc 15, is of rectangular shape and of a size slightly less than the size of the opening 16 whereby the plate may be pulled thru the opening for severing a substantial portion of the sealing disc when opening the bottle. The opposite end of the plate 21 is formed 50 55

with a hook 23 which preferably has a hinge connection with the inner end of the tongue 18 whereby the free end of the plate is held against the sealing disc. Connected at one end to the free end of the attaching portion 20 and extending rearwardly in overlying relation thereto, is a combined cover and lift plate 24 and this plate 24 aside from forming a cover over the opening 16, provides a lift which may be raised by one's fingers for opening the bottle. Striking out of the inner plate 21 provides a pair of spaced apart connecting arms 25 which serve to assist in holding the free end of the attaching portion 20 in position against the cap 10.

15 In use of the cap, one's finger is first placed at the free end of the lift plate 24 and the plate raised sufficiently to permit the same to be gripped between the fingers. Now, by pulling upon the lift 24 the inner plate 21 will swing 20 upwardly about the hook 23 as shown in Figure 5 thus severing a substantial portion of the sealing disc and pulling the severed portion of the disc outwardly thru the opening 16. As the plate 21 is raised, the sealing disc will be severed along 25 the sides of the opening 16 by the blades 17. When desiring to close the bottle after partially removing its contents, the connecting arms 25 will engage the top portion 11 to limit inward movement of the opener.

30 Referring now to the form of invention as disclosed in Figures 8 to 14 inclusive, the form of bottle cap or closure shown therein comprises a metallic cap 26 embodying a disc-shaped top portion 27 provided about its edge with the scalloped flange 28 to be crimped about the end of the bottle A. Formed in the top portion 27 of the cap 26 is an elongated, preferably rectangular-shaped opening 29 provided along each of its longer side edges with an inwardly extending 35 blade or cutter 30 formed integral with the top portion and having a depth less than the thickness of the sealing disc 31.

The opener member designated as a whole by the numeral 32 is formed of suitably thin sheet 40 metal and embodies an outer or major portion 33 shown in detail in Figure 13 and an inner plate portion 34 shown in Figure 14. The outer or major opener portion 33 is of one-piece construction providing an attaching portion 35 and a 45 combined cover and lift plate 36 bent to extend in overlying relation to the attaching portion 35. The outer opener portion 33 is of substantially rectangular shape and of a size slightly larger than the opening 29 in the cap 26 as shown in Figures 10 and 11. The attaching portion 35 is secured at its free end as by soldering, welding, or the like to the outer side of the top portion 27 beyond one end of the opening 29. Struck inwardly from the attaching portion 35 adjacent 50 each end thereof are tongues or arms 38 which are adapted to extend with a sealed fit thru the sealing disc 27 adjacent opposite ends of the opening 29.

The inner plate portion 34 which is adapted to 55 engage upon the inner side of the sealing disc 27 is of rectangular shape and of a size substantially equal to the size of the opening 29, with the width of the plate being slightly less than the spacing between the blades 30 to permit the plate 60 to be pulled thru the opening. The inner plate portion 34 is provided adjacent each end with a slot 40 for receiving the ends of the arms 38 which extend thru the slots and preferably have their ends bent over upon the inner plate as 65 clearly shown in Figure 10. In order to prevent

the bent ends of the arms 38 from possibly straightening out and pulling thru the sealing disc, the arms may be secured as by soldering or the like as at 42. This soldering 42 will not be absolutely required if the opener portion 33 is formed of heavy gauge metal altho it is preferred that the opener be formed of metal sufficiently thin to permit ready raising of the lift plate 36 by one's finger and without requiring use of any instrument. The inner plate 34 will insure severing 10 of a substantial portion of the sealing disc 27 so that a suitably large hole is formed thru the closure cap.

Thus, in both forms of the invention there is a metallic plate arranged inwardly of the sealing disc and connected thru the sealing disc with an outer opener portion providing means whereby a pull may be exerted upon the inner plate to pull the inner plate thru an opening in the metallic cap and thus sever a portion of the sealing disc.

Changes in detail may be made to the forms of invention herein shown and described, without departing from the spirit of the invention or the scope of the following claims.

I claim:

1. A bottle closure comprising a cap provided with a rectangular shaped opening, a sealing disc in the cap and covering said opening, a one piece plate portion overlying the inner side of the sealing disc and conforming to the shape of the opening, a swinging lift secured at one end to the outer side of the cap and projecting beyond the margin of the opening, and means connecting opposite ends of the plate portion to opposite ends of said lift for movement thru said opening upon swinging movement of the lift for severing a substantial portion of the sealing disc.

2. A bottle closure comprising a metallic cap having an opening formed in the top portion thereof, a sealing disc arranged inwardly of the cap, a lift secured to the cap at one end of said opening, a plate portion inwardly of the sealing disc in alignment with the opening, and means extending thru the sealing disc for securing the plate portion at opposite ends for movement outwardly thru said opening by the lift.

3. A bottle closure comprising a metallic cap having an opening formed in the top portion thereof, a sealing disc arranged inwardly of the cap, a lift overlying the top portion and projecting beyond the margin of the opening, means securing the lift to the cap at one end of said opening, a plate inwardly of the sealing disc in alignment with and conforming to the shape of the opening, and arms extended thru the sealing disc and connected to opposite ends of said plate for causing outward swinging and severing of a portion of the sealing disc upon pulling on said lift.

4. A bottle closure comprising a metallic cap having an opening formed in the top portion thereof, a sealing disc arranged inwardly of the cap, and an opener comprising an attaching portion secured at one end to the top portion at one end of said opening, a lift plate secured at one end to the free end of the attaching portion and normally covering said opening, arms struck inwardly from the attaching portion and projecting thru the sealing disc, and a plate at the inner side of the sealing disc and connected adjacent 70 opposite ends to said arms.

5. A bottle closure comprising a metallic cap having an opening formed in the top portion thereof, a sealing disc arranged inwardly of the cap, and opener means for the closure comprising 75

5 a one piece outer portion including an attaching portion secured at one end to the top portion at one end of said opening and a lift plate overlying the attaching portion above said opening, an arm struck inwardly from each end portion of the attaching portion and projecting thru the sealing disc adjacent opposite ends of said opening, and an inner plate disposed at the inner side of the disc and having apertured ends for securing said

10 arms to the plate.

6. A bottle closure comprising a metallic cap having an opening formed in the top portion thereof, a sealing disc arranged inwardly of the cap, opener means for the closure comprising a

one piece outer portion including an attaching portion secured at one end to the top portion at one end of said opening and a lift plate overlying the attaching portion above said opening, an arm struck inwardly from each end portion of the attaching portion and projecting thru the sealing disc adjacent opposite ends of said opening, a plate disposed inwardly of the sealing disc and having a slot at each end thereof to receive the inner ends of said arms which are bent over 10 the plate, and means for securing the bent ends of the arms to the plate to prevent the bent ends from pulling out of said slots.
